US0D1095398S

(12) **United States Design Patent** (10) Patent No.: **US D1,095,398 S**
(45) Date of Patent: ** Sep. 30, 2025

(54) **TIRE**

(71) Applicant: **COMPAGNIE GENERALE DES ETABLISSEMENTS MICHELIN, Clermont-Ferrand (FR)**

(72) Inventors: **Olivier Spinnler, Clermont-Ferrand (FR); Adrien Traverse, Clermont-Ferrand (FR); Frédéric Massis, Clermont-Ferrand (FR)**

(73) Assignee: **Compagnie Generale des Etablissements Michelin, Clermont-Ferrand (FR)**

(**) Term: **15 Years**

(21) Appl. No.: **29/924,553**

(22) Filed: **Jan. 19, 2024**

(51) LOC (15) Cl. **12-15**

(52) U.S. Cl. **D12/588**
USPC ....

(57) **CLAIM**

The ornamental design for a tire, as shown and described.

DESCRIPTION

FIG. 1 is a perspective view of the tire of our design; FIG. 2 is a front elevation view of the tire of our design; FIG. 3 is a side elevation view of the tire of our design; FIG. 4 is a side elevation view of the tire of our design, taken from the opposite side of that shown in FIG. 3; and, FIG. 5 is an enlarged, partial view of the tire of our design, taken from FIG. 1. The dash-dot-dot-line defines the boundaries of the claim. The broken line disclosure in the drawings depicts environmental subject matter forming no part of the
